UNITED STATES PATENT OFFICE.

CHARLES M. WILCOX, OF NEW PARIS, OHIO.

FEED-WATER APPARATUS.

SPECIFICATION forming part of Letters Patent No. 226,141, dated March 30, 1880.

Application filed January 19, 1880.

To all whom it may concern:

Be it known that I, CHARLES M. WILCOX, of New Paris, in the county of Preble and State of Ohio, have invented certain new and 5 useful Improvements in Feed-Water Apparatus; and I do hereby declare that the following is a full, clear, and exact description of the invention, which will enable others skilled in the art to which it appertains to make and 10 use the same, reference being had to the accompanying drawing, which forms a part of this specification, and in which the drawing represents a side elevation.

This invention relates to devices for feeding 15 boilers without the use of feed-pumps or similar apparatus; and it consists in the construction and combination of parts of a vacuum feed-water apparatus, substantially as herein-after more fully described.

20 In the drawing, A is the boiler, which may be of any suitable size and construction. B is a tank or reservoir, located some distance above the boiler, with which it communicates through a steam-pipe, C, and water-pipe D, arranged as shown on the drawing. E is a supply-pipe, which extends from the well F up to the reservoir B, which is further provided with a funnel, b. The letters c, d, and e denote stop-cocks on pipes C, D, and E, respectively, by which these may be closed or opened, 25 as required in operating the apparatus.

The operation is as follows: The tank or reservoir B is filled with water through its funnel b or supply-pipe E, after which the 30 boiler is fed by opening pipe D. When the

boiler has received a sufficient amount of water, pipe D is closed and pipe C is opened, which lets steam into tank B and equalizes the pressure in this and in the boiler.

When it is desired to replenish the supply 40 of water in the boiler, pipe C is closed, when the steam contained in tank B will rapidly condense, (the funnel b being closed,) thus creating a vacuum. Pipe E is now opened, when the vacuum in the tank will draw the 45 water up and fill it, after which pipe E is again closed, while C and D are opened, and so on.

Having thus described my invention, I claim and desire to secure by Letters Patent 50 of the United States—

In a water-feeder for boilers, the combination, with a boiler, A, of the elevated water-tank B, the pipe D, entering the upper end of the boiler and connected by an elbow with a 55 cock, e, directly to the upper end of the reservoir or tank B, pipe C, connecting by a right-angled pipe with a cock, c, the lower end of the reservoir to the lower part of the boiler, the reservoir supply-pipe b, and well-pipe E, 60 having a cock, d, and connected to the reservoir B, all constructed and arranged substantially as shown and described.

In testimony that I claim the foregoing as my own I have hereto affixed my signature in 65 presence of two witnesses.

CHARLES M. WILCOX.
